UNITED STATES PATENT OFFICE.

JACOB READIGE ROSE, OF PHILADELPHIA, PENNSYLVANIA.

PORTABLE PHONOGRAPH.

1,424,681.

Specification of Letters Patent. Patented Aug. 1, 1922.

Application filed August 5, 1921. Serial No. 490,182.

To all whom it may concern:

Be it known that I, JACOB R. ROSE, a citizen of the United States, residing at Philadelphia, in the county of Philadelphia and 5 State of Pennsylvania, have invented new and useful Improvements in Portable Phonographs, of which the following is a specification.

This invention relates to phonographs 10 and has for its object the provision of a phonograph which is provided with a concavo-convex resonator between the tone arm and the amplifier whereby to improve the quality of sound given out by the device.

15 An important object is the provision of a phonograph in which the cabinet is formed with a relatively small compartment within which the tone arm and reproducer may be packed when not in use, the cabinet having 20 a cover which closes down and encloses the turn-table whereby the entire structure will be encased.

Another object is the provision of a storage compartment in the cover for the purpose of holding the disk records used in connection with the machine.

25 An additional object is the provision of a device of this character which will be simple and inexpensive in manufacture, easy to 30 set up and knock down, efficient in use, durable in service, and a general improvement in the art.

With the above and other objects and advantages in view, the invention consists in 35 the details of construction to be hereinafter more fully described and claimed and illustrated in the accompanying drawings in which—

Figure 1 is a vertical sectional view 40 through my device with the cover in open position,

Figure 2 is a plan view thereof,

Figure 3 is a detail sectional view showing the compartment door open, and

45 Figure 4 is an enlarged detail sectional view through the resonator.

Referring more particularly to the drawings, I have shown my device as comprising a rectangular casing 10 within which is 50 cured a horizontal plate 11 constituting the top of the amplifier chamber 12. Journaled at substantially the center of this plate 11 is the usual turn-table 13 which supports the records during the playing thereof.

The numeral 14 indicates, conventionally, 55 the speed control indicator and the numeral 15 indicates the usual lever used for starting and stopping. The usual spring motor mechanism is provided but is not shown as forming no part of the present invention. 60 At one corner the plate 11 is formed with a circular hole 16 within which is engaged a downwardly extending concavo-convex metallic member 17 which is provided with an outwardly extending flange 18 engaging 65 upon the top of the plate 11. At its center this member 17 is formed with a socket 19, for a purpose to be described.

The numeral 20 designates the tone arm which carries the usual reproducer 21. Secured within the lower down-turned end of the tone arm is a transverse rib 22 within the center of which is secured a spindle 23 which seats revolubly within the socket 19. By this means it will be seen that the tone 75 arm 20 may move as the reproducer moves along the record during the playing operation.

Located within the casing 10 near one end thereof, is a transverse partition 24 which 80 defines a storage compartment 25 into which leads an opening 26 in the plate 11 normally closed by a hinged spring-pressed door 27 having a handle 28. When the device is not in use the tone arm is lifted 85 off, the spindle 23 pulling out of the socket 19, after which the tone arm and reproducer are passed through the opening 26 and stored within the compartment 25. The crank handle 29 used for winding the 90 spring motor may also be removed and placed within this compartment.

Hinged upon one edge of the casing 10 is a cover 30 which is adapted to be held closed by suitable catches 30 and this cover 95 is provided near its open side with a hinged board or plate 31 upon the free edge of which is hinged a second board or plate 32. These two plate members 31 and 32 cooperate with the top of the cover to define a 100 compartment 33 within which may be stored the disk records not being played. The hinge connection of the members 31 and 32 is of the spring type and both of these members are held in closed position by a 105 suitable spring catch 34.

When the device is in use the cover 30 is opened and the tone arm is placed in posi-

tion with the finger 23 seating within the socket 19, as shown in Figure 1. The device is used in exactly the same manner as any other phonograph. When the device is not in use all the records are packed within the compartment 33 and the tone arm and reproducer are packed away in the compartment 25, as previously described, and the cover 30 is closed and locked. The casing 10 is provided at one edge with a suitable handle 35 by means of which it may be easily carried.

From the foregoing description and a study of the drawings it will be apparent that I have thus provided a simply constructed and consequently inexpensive phonograph which will be easily portable and which will therefore recommend itself for use on auto trips, picnics, camping parties, and the like, and in fact in all places and under such circumstances as would prohibit the use of the usual cumbersome machine. It is to be noted that the peculiarly constructed resonator employed

will insure the emission of notes or tones 25 of fine quality.

While I have shown and described the preferred embodiment of my invention, it is of course to be understood that I reserve the right to make such changes in the form, 30 construction and arrangement of parts as will not depart from the spirit of the invention or the scope of the subjoined claim.

Having thus described my invention, I claim:

In a talking machine including a cabinet, and a sound board therein, the sound board being provided with a hole, a downwardly extending concavo-convex shell seating within said hole and provided at its center 40 with a bearing socket, and a tone arm having one end carrying a reproducer and provided at its other end with a spindle revolvably seating within said socket.

In testimony whereof I affix my signature.

JACOB READIGE ROSE.
